CLAIM

The ornamental design for a wood burning fireplace, as shown and described.

DESCRIPTION

FIG. 1 is a side-top perspective view of an embodiment of a wood burning fireplace showing my new design;

FIG. 2 is a front elevational view of the wood burning fireplace shown in FIG. 1;

FIG. 3 is a rear elevational view of the wood burning fireplace shown in FIG. 1;

FIG. 4 is a right side elevational view of the wood burning fireplace shown in FIG. 1;

FIG. 5 is a left side elevational view of the wood burning fireplace shown in FIG. 1;

FIG. 6 is a top plan view of the wood burning fireplace shown in FIG. 1;

FIG. 7 is a bottom plan view of the wood burning fireplace shown in FIG. 1; and,

FIG. 8 is a bottom-side perspective view of the wood burning fireplace shown in FIG. 1.

The dash-dash broken lines show portions of the wood burning fireplace that form no part of the claimed design. The dot-dash-dot broken lines depict the boundaries of the claim and form no part thereof.

1 Claim, 6 Drawing Sheets
